UNITED STATES PATENT OFFICE.

JOHN F. STREIB, OF AVALON, PENNSYLVANIA, ASSIGNOR TO PRESSED STEEL CAR COMPANY, OF PITTSBURGH, PENNSYLVANIA, A CORPORATION OF NEW JERSEY.

CAR CONSTRUCTION.

1,177,829.

Specification of Letters Patent.

Patented Apr. 4, 1916.

Application filed September 27, 1911. Serial No. 651,490.

To all whom it may concern:

Be it known that I, JOHN F. STREIB, a citizen of the United States, residing at Avalon, in the county of Allegheny and State 5 of Pennsylvania, have invented certain new and useful Improvements in Car Construction, of which the following is a specification.

My invention relates to railway cars and 10 has for its principal object the construction of a car, which for a given capacity, will have the maximum width within the clearance limits allowed; and yet permit of the application of safety appliances, such 15 as side ladders and hand holds, to the outer side of the car, as required by the recent order of the Interstate Commerce Commission, without reducing the width of the car throughout the entire length of its body 20 and consequent reduction of cubic capacity. To attain this object I construct a car, the body or load retaining portion of which is widest at the middle portion of its length, *i. e.*, from bolster to bolster or thereabout, 25 the end portions of the sides, *i. e.*, those portions between the bolsters and the ends of car, being set back in the direction of the longitudinal center line of the car a sufficient distance to permit of the side ladders and hand holds being attached thereto 30 and yet not project beyond the vertical plane of the outside of the side plate of the middle portion of the car.

Referring now to the drawings in which 35 like reference characters refer to like parts and in which:—

Figure 1 is a top plan view of a car underframe, parts of the body being shown in section; Fig. 2 is a side elevation of the 40 car; Fig. 3 is an end elevation of the car; Fig. 4 is a sectional view on the line 4—4 Fig. 2, and Figs. 5, 6, 7 and 8 are sectional views showing modifications of the invention.

45 The description being confined to that portion of the car which is illustrated it will be understood that the opposite end of the car is in all respects similar to that which is shown.

50 Referring now in detail to the drawings, 1 indicates the center sills, 2 the end sill, 3 the bolster comprising angle bars 4, a web plate 5 and a bottom tie plate 6, and 7 in-

dicates the short side sills at the side of the car, which extend from the end sill to 55 the bolster.

At the ends of the bolster 3, the car is provided with stakes 8 of Z or other suitable section, the webs 9 of which extend transversely of the car in the direction of 60 their width and, at their lower end, are adapted to be secured to the web plate 5 of said bolster 3 by rivets 10. The flanges 11 and 12 of the stakes 8 being in different vertical planes and extending in the direction of 65 the length of the car on both sides of the web 9, afford convenient means for connecting the side plates 13 of the narrowest portions of the car and the side plates 14 of the widest portion of the car. Besides being 70 secured to the web plate 5 the stakes 8 are secured at their lower ends to the side sills 7.

15 indicates the end plate extending from side to side of the car, secured at the corners to the end side plates 13 by means of angle posts 16, the flanges of which are riveted to both end and side plates. To 75 strengthen the end of the car an angle bar 17 is riveted to the top of the end plate 15. 80

18 indicates angle bars which extend along the top of the car and are secured at their ends to the angle bar 17 by a gusset plate 19. At the widest portion of the car the vertical flanges 18^a of the angle bars 18, 85 are secured to the top of the side plates 14. To strengthen the car side at the narrowest portions of the car the side plates 13 are flanged outwardly along their top edges and are secured to the inside faces of the flanges 90 21 of the angle bars 18.

Fig. 5 illustrates a modified form of the invention in which the end side plate 13 is provided with an outwardly extending flange 20 and the center side plate 14 is provided with an inwardly extending flange 95 21, the bottom portions of these flanges 20 and 21 are secured to the web plate 5 of the bolster 3. Above the web plate 5 a filler 22 is secured between the flanges 20 and 21 by 100 rivets, bolts or other means. This filler together with the flanges 20 and 21 forms a strong stake at the bolster.

Fig. 6 illustrates another modified form of the invention, in which a channel 24 is 105 used to connect the end side plate 13 and

the center side plate 14. The web 25 of the channel 24, extends transversely of the car in the direction of its width, the lower end of which is adapted to be secured to the web plate 5 of the bolster 3. The flange 26 of the channel 24, being in substantially the same vertical plane as the end side plate 13, is secured to such side plate 13 by rivets, bolts or other means, while the flange 27 being in a different vertical plane is secured to the center side plate 14.

Fig. 7 illustrates another modified form of the invention in which two angle bars 28 and 29 are used to connect the end side plate 13 and the center side plate 14. The flange 30 of the angle bar 28 extends transversely of the car, away from the longitudinal center line, while the flange 31 of the angle bar 29 extends transversely of the car toward the longitudinal center line, these flanges are secured together back to back by rivets 32, and their lower ends are secured to the bolster web plate 5, of the bolster 3. The flange 33 of the angle bar 28 is secured to the end side plate 13 and the flange 34 of the angle bar 29 is secured to the center side plate 14.

Fig. 8 illustrates another modified form of the invention in which an angle bar 34 is used to connect the end side plate 13 and the center side plate 14. The flange 35 of the angle bar 34 extends longitudinally of the car and in the direction of the longitudinal center line of the car and is secured to the center side plate 14, while the flange 36 extends transversely toward the longitudinal center line of the car, and near the bottom is secured to one side of the web plate 5 of the bolster 3. The end side plate 13 is provided with an outwardly extending flange 37 the lower portion of which is secured to the other side of the web plate 5 of the bolster 3. Above the bolster and between the flange 37 of the side plate 13 and the flange 36 of the angle bar 34 a filler 38 is secured.

What I claim is:—

1. In a car side, the combination with an end side plate having an outwardly extending flange along its top edge, of a center side plate, said end side plate being in a different vertical plane to said center side plate, a stake connecting said side plates, and a member secured along the top edge of said center side plate and to the flange of said end side plate.

2. In a car side, the combination with an exterior side plate, of a second side plate, said second exterior side plate being in a different vertical plane to first said side plate, and a stake of Z section located between and connecting said plates to each other.

3. In a car, the combination with a bolster, of a bolster web plate, side plates, one

of said side plates being in a different vertical plane to the other, a filler interposed between said side plates and secured to said bolster web plate.

4. In a car, the combination with a bolster of a stake secured to said bolster, side plates, one of said side plates being in a different vertical plane to the other and both of said plates being secured to said stake. 76

5. In a car side, the combination with a center side plate extending from bolster to bolster, of an end side plate extending from the end of the car to the bolster in a different vertical plane but not co-extensive with the first mentioned side plate and means connecting both of said plates together. 75

6. In a car side, the combination with a single side plate, of a second side plate in a different vertical plane but not co-extensive with the first mentioned plate, a filler interposed between said plates, and a member extending from end to end of the car body and secured along the top edges of said plates. 85

7. In a car side, the combination with an exterior side plate of a second exterior side plate, said second side plate being in a different vertical plane to first said side plate, and a stake of Z section connecting said plates to each other. 95

8. An open top car having a wide central body portion extending from bolster to bolster, and contracted end body portions each extending from the bolster to the end of the car. 100

9. A dump car having a wide central body portion extending from bolster to bolster, and narrow end body portions extending from said bolsters to the ends of the car. 105

10. A side for freight car bodies having a single sheathing comprising a plurality of plates in different vertical planes and a vertically disposed Z shaped stake interposed between and secured to said plates. 110

11. In a car side, a side plate extending from bolster to bolster only, in combination with side plates extending from the ends of the car to the bolsters only and in a different vertical plane from the first mentioned side plate. 115

12. In a car side, a side plate of single thickness extending from bolster to bolster only, in combination with side plates of single thickness extending from the ends of the car to the bolsters only and in a different vertical plane from the first mentioned side plate. 120

13. In a car side, a side plate of single thickness extending from bolster to bolster only, in combination with side plates of single thickness extending from the ends of the car to the bolsters only and in a different vertical plane from the first men- 125

tioned side plate, and vertically disposed fillers interposed between and secured to said plates.

14. In a car side, a side plate extending from bolster to bolster only, in combination with side plates extending from the ends of the car to the bolsters only and in a different vertical plane from the first mentioned side plate, and a ladder mounted on one of said last mentioned plates within the vertical plane of the first mentioned plate.

15. In a car side, a side plate of single thickness extending from bolster to bolster

only, in combination with side plates of single thickness extending from the ends of the car to the bolster only and in a different vertical plane from the first mentioned side plate, and a ladder mounted on one of said last mentioned plates within the vertical plane of the first mentioned plate.

In testimony whereof I affix my signature in presence of two witnesses.

JOHN F. STREIB.
